HYGIENIC DISPENSER APPARATUS

Samuel G. Berkow, Perth Amboy, N.J., assignor to Menlo Park Laboratories, Inc., Edison, N.J., a corporation of New Jersey

Filed Mar. 21, 1961, Ser. No. 97,261
4 Claims. (Cl. 128—225)

This application is a continuation-in-part of my co-pending application Serial No. 861,074 filed December 21, 1959, for "Hygienic Dispenser Apparatus," now abandoned.

This invention relates to hygienic dispenser apparatus.

An object of this invention is to provide apparatus of the character described comprising a container or bottle having a neck, a valve on the neck including a tiltable outlet tube, so constructed that tilting of the outlet tube will open the valve, so that propellant gas under pressure in the container, will expel medicament through the outlet tube, and a nozzle comprising a nozzle tube with a rearwardly and outwardly flaring portion at its rear end, frictionally fitted on the tip of the outlet tube coaxially thereto, and surrounding the neck and valve of the container in spaced relation thereto, the arrangement being such that pressure on one side of the flaring portion will tilt the outlet tube so that the valve opens for discharge of materials from the container through the nozzle tube.

A further object of this invention is to provide a device of the character described in which the nozzle tube has a front tapering nose, with holes in the tapering nose so that material from the container will be discharged in forwardly and outwardly inclined streams when the valve is opened.

Another object of this invention is to provide a device of the character described in which the outer diameter of the flaring portion is greater than the diameter of the container or bottle, to facilitate cleanliness during tilting of the nozzle, relative to the bottle.

Yet another object of this invention is to provide a device of the character described in which the flaring portion has at its rear end, an outwardly extending flat annular flange extension to give greater leverage for tilting and to keep the fingers away from the user's body during tilting.

Still another object of this invention is to provide a device of the character described in which the length of the nozzle tube forwardly of the flaring cone portion is two inches or less in length, so as to ensure that the cervix of the user is not contacted when the device is used for vaginal treatment.

A still further object of this invention is to provide in a device of the character described, a nozzle in which the nozzle tube as well as the flaring cone portion are ribbed for strength, and in which the outer periphery of the annular flat flange has a rearwardly extending head for strength and rigidity, to enable the user to press against said outer periphery for effecting a tilting movement of the outlet tube, to open the valve.

Another object of this invention is to provide in a device of the character described, a nozzle having a front central tubular portion provided at its front end with outlet discharge openings, outwardly and rearwardly flaring portions at the rear end of the front tubular portion, and a rear tubular portion communicating with the front tubular portion, and extending rearwardly from the hub of the flaring portion, and having means at its rear end to frictionally and slidably receive the front end of the outlet tube of the bottle, whereby to space the flaring portion forwardly of the neck of the bottle to make for better leverage for easier tilting of the outlet tube to open the bottle valve for discharge of materials therefrom.

Yet another object of this invention is to provide a

2

strong, durable and sanitary device of the character described which shall be relatively inexpensive to manufacture, easy to manipulate, comfortable in use and practical and efficient to a high degree.

5 Other objects of this invention will in part be obvious and in part hereinafter pointed out.

The invention accordingly consists in the features of construction, combination of elements, and arrangement of parts, which will be exemplified in the construction hereinafter described, and of which the scope of invention will be indicated in the following claims.

In the accompanying drawings in which is shown an illustrative embodiment of the invention,

15 FIG. 1 is a perspective view of a device embodying the invention;

FIG. 2 is an enlarged cross-sectional view taken on line 2—2 of FIG. 1;

FIG. 3 is a perspective view of the device illustrating tilting of the nozzle;

20 FIG. 4 is an enlarged cross-sectional view taken on line 4—4 of FIG. 1;

FIG. 5 is a cross-sectional view illustrating use of the device for vaginal treatment;

25 FIG. 6 is a view similar to FIG. 4 but illustrating a modified form of the invention;

FIG. 7 is a view similar to FIG. 3 and illustrating use of the device of FIG. 6;

FIG. 8 is an enlarged front end view of the discharge tip of the nozzle of FIG. 6; and

FIG. 9 is a perspective view of a rear extension tube fixed to the rear of the front tube of the nozzle of FIG. 6.

Referring now in detail to the drawing, 10 designates a device or apparatus embodying the invention. The same 30 comprises a container or bottle 11 and a nozzle member 12 fitted thereon.

The bottle 11 has a sloping shoulder 13 from which extends a neck 14 at its upper end. Mounted on said neck 14 is a valve assembly 15. Said valve assembly 15 comprises a washer 16 mounted on the top edge of neck 14. 40 Mounted on the washer 16 is a member 17 having a top annular flange 18 resting on washer 16. Extending down from flange 18 is a central annular, cylindrical portion 19 passing through a central opening 16a in washer 16. Extending from the lower end of annular or cylindrical portion 19 is a shoulder 20 from which projects downwardly, an inlet tube 21.

45 Mounted on member 17 is a member 25 having a cylindrical portion 26 fitted within cylindrical portion 19 of member 17, but terminating above shoulder portion 20. 50 Extending from the upper end of portion 26 is an annular flange 27 lying on portion 18 of member 17. Said flange 27 is formed with a central annular raised hub 29 providing an annular outer shoulder 30. Member 25 is preferably made of rubber or rubber-like, soft resilient material.

55 Mounted on member 25 is a member 35 made of rigid plastic or the like material and comprising an axial tubular portion 36, the lower end of which projects down into cylindrical portion 26 of member 25. Said tubular portion 36 projects up above member 25. At its lower end, tubular portion 36 has an integral bottom wall 38 located in spaced relation above the lower end of cylindrical portion 26. Said tubular portion 36 is formed with a pair of opposed openings 39 adjacent bottom wall 38.

60 Said tubular portion 36 also has an external annular collar 40 resting on hub 29. Said collar 40 has at its upper surface, an annular groove 41 for the purpose hereinafter appearing.

A closure cap 50 made of metal, has an annular wall 51 surrounding the upper end of the neck 14 and the outer edges of flange 18 and washer 16. Said cap further comprises an inwardly curved lower end 52 engaging a constricted portion 14a of neck 14 to keep the cap on the

bottle. Said cap further comprises an annular horizontal portion 53 contacting the top of flange 18 adjacent periphery of the latter.

Extending from portion 53 is an upwardly recessed or raised portion 54 contacting flange 27 of member 25. Said raised portion 54 contacts shoulder 30 of hub 29. Extending upwardly from the inner end of portion 54 is a cylindrical portion 55 from which extends an inwardly rolled portion 56 engaging groove 41 of collar 40.

Thus, cap 50 clamps members 25 and 17 to washer 18 which is clamped to the upper edge of the neck of the bottle.

It will now be understood that tilting of member 35 will press against portion 26 of the rubber-like member 25 and open one of the holes 39 to allow gas under pressure in the bottle to force liquid or other material within the bottle up and out of tubular portion 36.

Said bottle 11 and valve assembly 15 are old and well known in the art, and no claim is made thereto per se.

Fitted on the upper end of the tubular portion 36 is the nozzle member 12. Said member 12 may be made of polyethylene, which can be sterilized by boiling, or of polypropylene, which can be auto-claved or boiled for sterilization.

Said nozzle 12 comprises a tubular portion 60, formed at its front end with a nose 61 which may be substantially semi-hemispherical or conical or tapered in shape. Said nose 61 is formed with a central, external forwardly projecting lug 62. Said nose is formed, adjacent the central lug, with four equiangularly spaced, longitudinal, transversely arcuate slots or openings 63 in the tapered wall of the nose.

At the lower end of tubular portion 60 is a thickened hub or boss 65 having an outer conical surface 66 merging with the outer surface of tube 60. Said hub also has a lower, flat undersurface 67. The diameter of the inner surface 60a of tubular portion 60 is less than the outer diameter of tubular portion 36. Said hub or boss 65 is formed, at its underside, with a central counterbore 68 from which extends a second reduced axial counterbore 69 only slightly larger in diameter than inner surface 60a. Opening 69 may be about .006" greater in diameter than surface 60a and frictionally fits on the upper end of tubular portion 36. The upper end of tubular portion 36 contacts the shoulder at the upper end of opening 69. Said opening 69 is only about $\frac{1}{8}$ " in length. Thus the undersurface 67 of hub 65 is held away from cap 50.

Extending from hub 65 is a frusto-conical or flaring portion 75. Said portion 75 makes a smaller angle with the axis of nozzle 12 than surface 66.

Said portion 75 extends to a level below the neck 14, but short of the shoulder 13 of the bottle and is spaced from the cap 50 and said neck and shoulder.

Extending outwardly from the rear end of portion 75 is a flat annular flange 77, and extending rearwardly from said flange, adjacent its outer periphery, is a thickened annular bead 78. Said bead is also spaced from the shoulder of the bottle. The diameter of the periphery of flange 77 is preferably greater than the outer diameter of the bottle 11.

Said tube 60 is formed with a plurality of external reinforcing ribs 60b. The ribbing extends as at 66a on surface 66, and as at 75a on portion 75 and as at 77a on flange 77, continuously.

Tube 60 is preferably under 2" in length. The apparatus may be used for vaginal douche or medication.

In use, the bottle may be held in one hand by the user and the tube 60 inserted into the vagina. Since the tube is short, it will not contact the cervix. The user may press a finger against the flange 77 and tilt the bottle 11 relative to the nozzle, to open the valve so that the medication will be forced through openings 63 in four streams which are inclined forwardly and outwardly.

Any suitable medication may be used. It may include a quaternary, lactic acid and a buffering agent. Any vaginal

cleanser may be used. The aerosol propellant may be "Genetron," which is well known.

The angular streams and the shortness of length of tube 60 prevents intromission into the cervical canal. The greater outer diameter of the cone prevents entrance too far into the vagina and also closes the vagina to keep the pressure from dissipating. The wide flange 77, being wider than the bottle, makes for cleanliness as it keeps the fingers away from the vagina.

The hub 65 strengthens the nozzle at the middle, and the rim 78 strengthens the rim of flange 77.

The diameter of the flange 77 is preferably greater than the length of tube 60.

Referring now to FIGS. 6 to 9, there is shown a nozzle 100 illustrating a modified form of the invention. Said nozzle 100 comprises a front nozzle portion 12a substantially similar to nozzle 12 of FIGS. 1-5.

Said nozzle portion 101 comprises a tubular portion 60c formed at its front end with a nose 61a which may be substantially hemispherical or conical or tapered in shape. Said nose 61a is formed with four, equiangularly spaced, transversely arcuate slots or openings 63a in the tapered wall of the nose.

At the lower end of the tubular portion 60c is a thickened hub 65a having an outer conical surface 66b. Said hub also has a lower, flat annular undersurface 67a. Said hub or boss 65a is formed, at its underside with a central upwardly extending counterbore 68a from which extends upwardly a second reduced axial counterbore 69a.

Extending from hub 65a is a rearwardly and outwardly flaring frusto-conical portion 75b making a smaller angle with the axis of the nozzle than surface 66b.

Extending outwardly from the rear of flaring frusto-conical portion 75b is a flat annular flange 77b, and extending rearwardly from flange, adjacent its outer periphery, is a thickened rearwardly extending annular bead 78a.

Said tube 60c is formed with a plurality of external reinforcing ribs 60d. The ribbing extends as at 66c on surface 66b, and at 75c on portion 75b, and as at 77c on flange 77b, continuously.

Fixed to the rear of hub 65a is an extension tube 102 comprising a portion 103 having an outer cylindrical surface 104. At the front end of surface 104 is an annular reducing shoulder 105 from which extends a reduced tubular portion 106. Portion 106 fits into countersunk opening 69a. The front end of portion 103 fits into countersunk opening 68a. Said tube has a through axial opening 110 communicating with tubular portion 60c. at the rear end of tubular opening 110 is an enlarged countersunk opening 111. Tube 102 is either force-fitted into openings 69a, 68a or it is adhered thereto, or tube 102 may be integrally made with nozzle 12a.

In FIG. 6 is shown bottle or container 11 same as shown in FIGS. 1-5. The front end of tiltable tube 36 of said bottle is frictionally and slidably fitted into the countersunk opening 111. The valve of the bottle is actuated in the same way as shown in FIG. 3. The advantage of the construction of FIGS. 6-9 is that a greater leverage is available for easier actuation of the valve, due to the extension tube.

It will thus be seen that there is provided an apparatus in which the several objects of this invention are achieved, and which is well adapted to meet the conditions of practical use.

As possible embodiments might be made of the above invention, and as various changes might be made in the embodiment above set forth, it is to be understood that all matter herein set forth or shown in the accompanying drawings, is to be interpreted as illustrative and not in a limiting sense.

I claim:

1. In combination, a bottle containing a propellant gas and liquid to be discharged, said bottle having a neck,

a valve on said neck including a tilttable rigid outlet tube and means to open the valve when said tube is tilted.

5 a nozzle on and coaxial with said tube formed at the front end with discharge openings,

and at its rear end formed with a rearwardly and outwardly flaring portion, rigid with said nozzle, said flaring portion terminating in a flange perpendicular to and coaxial with said nozzle and said flange having a reinforcing downwardly directed bead, and reinforcing ribs extending rearwardly and outward-

10 ly along the flaring portion to lend rigidity to said portion, said flange and reinforcing ribs and bead enabling an operator with one hand to grasp the bottle and to finger engage the flange to tilt the 15 nozzle.

2. The structure of claim 1 wherein the inner diameter of the bead is greater than the outer diameter of the bottle.

3. The structure of claim 1 wherein the reinforcing 20 ribs are prolonged to extend radially of the flange.

4. In combination, a bottle containing a propellant gas and liquid to be discharged, said bottle having a neck, a valve on said neck including a tilttable rigid outlet tube and means to open the valve when said tube is tilted, a nozzle coaxial with said tube and having a forwardly

extending tubular portion formed at the front end with discharge openings, and with a rearwardly and outwardly flaring portion rigid with said tubular portion, said tubular portion having at its rear end a central rearward extension tube, the rear end of which frictionally and slidably receives the tip of said tilttable tube in order to retain said flaring portion in spaced relation to said bottle to afford increased leverage in tilting the tube and to prevent said flaring portion from touching the sides of the bottle except at the neck portion, thereby enabling wide opening of the valve.
